(57) **CLAIM**

The ornamental design for a livestock stick, as shown and described.

DESCRIPTION

FIG. 1 is a front perspective view of a livestock stick, showing my new design;

FIG. 2 is a rear perspective view thereof;

FIG. 3 is a front elevation view thereof;

FIG. 4 is a rear elevation view thereof;

FIG. 5 is an enlarged left side view thereof;

FIG. 6 is an enlarged right side view thereof;

FIG. 7 is a top plan view thereof;

FIG. 8 is a bottom plan view thereof;

FIG. 9 is an enlarged view of the portion outlined in FIG. 1;

FIG. 10 is an enlarged view of the portion outlined in FIG. 2;

FIG. 11 is an enlarged view of the portion outlined in FIG. 3;

FIG. 12 is an enlarged view of the portion outlined in FIG. 4;

FIG. 13 is an enlarged view of the portion outlined in FIG. 7;

FIG. 14 is an enlarged view of the portion outlined in FIG. 8;

FIG. 15 is a front perspective view of the livestock stick in a detached state; and,

FIG. 16 is a rear perspective view thereof.

The dash-dot-dash broken line represent boundaries for the enlarged views in FIGS. 1-4, 7-14 and form no part of the claimed design. The short dash-dash broken lines in the drawings illustrate portions of the livestock stick that form no part of the claimed design.

1 Claim, 13 Drawing Sheets
